UNITED STATES PATENT OFFICE.

CHARLES ALGERNON PARSONS, OF GATESHEAD ON-TYNE, COUNTY OF DURHAM, ENGLAND.

ROTARY MOTOR.

SPECIFICATION forming part of Letters Patent No. 391,071, dated October 16, 1883.

Application filed July 11, 1882. Serial No. 244,027. (No model.) Patented in France November 6, 1884, No. 165,199; in Belgium November 6, 1884, No. 66,794, and May 27, 1887, No. 77,622; in Germany November 7, 1884, No. 33,066, and May 28, 1887, No. 41,479; in Italy December 31, 1884, No. 484; in Sweden April 10, 1885, No. 990, and in England April 12, 1887, No. 5,312.

To all whom it may concern:

Be it known that I, CHARLES ALGERNON PARSONS, a subject of the Queen of Great Britain and Ireland, residing at Gateshead-on-Tyne, in the county of Durham, England, have invented Improvements in Rotary Motors Actuated by Elastic Fluid-Pressure, applicable also as pumps, (for which I have received patents in Great Britain April 12, 1887, No. 5,312; in France by certificate of addition, dated May 25, 1887, to Patent No. 165,199, dated November 6, 1884; in Belgium by patent of improvement, No. 77,622, dated May 27, 1887, to No. 66,794, dated November 6, 1884; in Germany by patent of addition, No. 41,479, dated May 28, 1887, to No. 33,066, dated November 7, 1884; in Sweden by Patent No. 990, dated April 10, 1885, and in Italy by Patent No. 484, dated December 31, 1884,) of which 20 the following is a specification.

My present improvements have reference to motors and pumps of the type described in the specification of my former patent, No. 328,710, dated October 20, 1885.

25 Figure 1 of the annexed drawings is a side elevation, partly in longitudinal section, of a motor embodying certain improvements hereinafter described, this motor being, however, constructed in the main on the principle set 30 out in my original specification. Figs. 2, 3, and 4 show alternative devices for preventing leakage past the motor-shaft, as hereinafter more fully explained.

In the motor illustrated in Fig. 1 the motive 35 fluid enters a central chamber, *a*, and from this central chamber it passes in succession through a number of motors of the turbine type, falling in pressure as it proceeds, and its velocity during its passage through the blades does not

40 greatly exceed that of the motor. So far the arrangement agrees with what is described in my original specification. In the construction described in that specification the space for the actuating-fluid increased either contin- 45 uously or step by step, the increase being gained either by an increased area or by an increased pitch of the blades, or both.

Now, according to my present improvements, the sets of turbines are similar to those de- 50 scribed in the preceding specification, and they are all fixed on one spindle, *b*. They are

of different diameters, the diameter being considerably increased step by step to allow the steam as it expands to flow through larger turbines, as well as those of greater pitch, as 55 before described. The arrangement is such that a higher circumferential velocity can be attained as the pressure falls.

In the arrangement illustrated by way of example in Fig. 1 there are six sets of turbines; 60 but other numbers or multiples of sets may be employed according to convenience or requirement. In the illustration the six sets constitute three pairs. Commencing from the center, *c* and *c'* constitute the first pair of sets of turbines. Their exhaust ends are connected by a passage, *d*. *c* and *c'* constitute the second pair of sets of turbines. The diameter of this pair is considerably larger than the diameter of the first pair, *c* and *c'*. The turbines *e* and *e'* are 65 connected by a passage, *f*. *g* and *g'* constitute a third pair of turbines. They are connected by a passage, *h*, through which the steam exhausts, it may be, to the atmosphere, or it may be to the condenser. The object of connecting 70 the exhaust ends of the cylinders of each pair of turbines by a passage, as described, (or there might be more than one such passage,) is to insure that the steam-pressures acting on the annular surfaces which are formed when a 75 larger turbine follows one of smaller diameter shall be kept equal, thus insuring that the spindle of the motor shall be preserved from end-pressure. In proportioning the turbines I endeavor to attain the best total aggregate 80 efficiency when leakage and slip are taken into account. The rate of increase of the diameters of the turbines is dependent on the initial and final steam pressures which are to be employed.

90 In some cases it will be convenient to supply the compound motor with steam at or near the atmospheric pressure and to exhaust into a condenser. Under these circumstances it is preferable to admit the steam at the ends of 95 the motor and to allow it to exhaust at the center. The smaller turbines are then placed at the ends of the spindle, the larger turbines being placed near the center of the spindle. If high-pressure steam be used and the exhaust 100 be delivered into a condenser, it is advantageous to make the joint at each end of the

spindle, where it emerges from the case or exterior cylinder of the motor, by water admitted to an annular groove around the spindle.

Figs. 2, 3, and 4 illustrate this improvement under different modifications. In each case *i* is an annular groove around the spindle, and *k* is a pipe by which water is admitted to the said annular groove. Such water can conveniently be obtained from the hot well or feed.

10 In Fig. 2 packing-rings are used similar to those employed in my original arrangement, the water admitted through the pipe *k* and space *i* forming an air-tight joint. In Fig. 3 the spindle is serrated by a spiral groove cut 15 in it to diminish the quantity of water drawn in by the vacuum of the condenser, and thus enable a smaller supply of water to staunch the joint. It has been found that such a groove or series of spiral grooves will have a 20 powerful action on water when the spindle is revolving at a high rate of speed.

Referring now to Fig. 4, it is found in practice that individual packing-rings of the kind shown in Fig. 4 do not wear well at very high 25 rates of speed when subjected to considerable fluid-pressure. Therefore, when exhausting into a condenser it is advantageous to use several such packing-rings in such a manner that the pressure shall distribute itself between 30 them. Such an arrangement is illustrated in Fig. 4, where there are three rings, *l l l*, and one ring, *m*, each running in a groove in the end of the cylinder. To the annular cavity around the spindle, as also to these grooves, a 35 small quantity of steam is admitted to prevent air being drawn into the condenser. This small quantity of steam may be drawn from the pressure-steam pipe or place of lower pressure in the motor; but it is preferable to control its 40 flow by a small equilibrium-valve, (not shown,) so as to maintain a pressure in the annular

space slightly above the pressure of the atmosphere.

What I claim is—

1. A rotary motor (or pump) comprising 45 two sets or series of cylinders arranged in pairs, the successive cylinders of each set or series being of larger diameter than the cylinder that precedes it, and passages connecting the exhaust ends of pairs of said cylinders, for the 50 purpose set forth.

2. A rotary motor (or pump) comprising cylinders arranged in pairs and passages, whereby the exhaust ends of the cylinders constituting each pair are connected, substantially as described, for the purpose specified. 55

3. In a rotary motor (or pump) comprising outer cylinders with rings of blades and inner cylinders with rings of blades mounted on a shaft or spindle to rotate within said outer 60 cylinders, a groove surrounding said shaft or spindle and supplied with water or steam to prevent air entering the exhaust-chamber and vitiating the vacuum with or without packing-rings, as described.

4. The improved rotary motor (or pump) comprising a central chamber, *a*, sets of turbines fixed on a spindle, *b*, said turbines consisting of three or other convenient number of pairs, the turbines having the exhaust ends of 70 those constituting each pair connected by passages, as described, and shown by *c c'* and *d*, *e e'* and *f*, and *g g'* and *h*.

In testimony whereof I have signed my name to this specification in the presence of two sub- 75 scribing witnesses.

CHARLES ALGERNON PARSONS.
